 assignors to The General Electric Company
 Limited, London, England

Application September 28, 1934, Serial No. 745,884
 In Great Britain October 5, 1933

6 Claims. (Cl. 187—29)

This invention relates to lift or like controlling systems, and has for its object the cheapening of such systems whilst at the same time improving in certain points on their reliability.

5 In connection with certain automatic or semi-automatic lift controlling systems, it is necessary that the control mechanism shall possess some indication of the position of the lift at any instant. This indication may be employed to determine, for example—the direction in which a lift is to travel when a calling or starting button is pressed, or to give a visual indication of the lift's position, or for like purposes. In this connection it is known to provide facsimile or reduction gearing operated directly or indirectly from the winding drum of a lift, which gearing drives a multi-contact switch affording the required indications. This method, though fairly certain in action, is costly and requires skilled maintenance.

10 15 20 25 30 35

An alternative known method of affording indication of a lift's position is to cause the said lift to supply current impulses at particular points in its travel to a group of non-self-maintained relays each one of which, to remain operated, must receive current continuously, the said relays operating or releasing and remaining thus positioned in sequence as the lift passes the said points. The objections to this method are that a current of greater or less dimensions is continuously employed in maintaining some or all of the relays energized, and that should this current supply fail, then even if the lift does not move, restoration of the current does not re-energize the relays necessary to afford indication of the lift's position.

According to the present invention, the impulses transmitted by the lift are received by, and operate, a chain of relays of a self-maintaining or two-position type such as that disclosed in British specification No. 354,847. The direction of operation of the chain is determined by the direction of travel of the lift.

Further, means are provided, according to the invention, whereby a facsimile of the position of a lift in a shaft is afforded by a group of relays each adapted to maintain itself in either one or two positions without the continuous use of current, the said group receiving an impulse of current each time the lift passes a predetermined point or points in the shaft.

Reference is now directed to the accompanying drawing of a circuit diagram of a system embodying the invention, which shows means for controlling a lift serving seven floors. All relays are shown in the positions occupied when the lift

is situated at the bottom floor. The lift L is suspended on a cable LC having a counterweight LW, the cable passing over a drum D operated by the motor M, a brake band BB being arranged to be operated by the brake magnet BM for releasing the brake for movement of the lift. The direction of travel of the lift is controlled by the two direction contactors UD and DD which control the motor M in cooperation with a slow down or speed control contactor DS. Each floor is provided with a gate switch GA to GG connected in series by leads 3A to 3G and by lead 3L in series with a lift or emergency switch GL on the lift car. These gate switches GL and GA to GG when closed complete the circuit of a gate relay FL operating a contact f_1 which will be normally closed when all the gate switches GL and GA to GG are closed.

Within the lift car and at each floor, floor push buttons PA to PG are arranged to operate circuit closing contact members connected by a common lead 4P through contacts sd_3 , dn_3 and up_3 with a positive potential at 5P, and by individual leads 6A to 6G with corresponding call storage relays CA to CG.

Each call storage relay CA to CG operates a corresponding contactor ca_1 to cg_1 to close a retaining circuit for the respective relays through leads 7a to 7g connected with a common lead 8 passing through a normally closed contact sd_2 to positive potential at 9.

Each of the call storage relays CA to CG is arranged to control the operation of two contactors ca_2 , ca_3 to cg_2 , cg_3 in a plurality of interconnected circuits arranged to normally short circuit the direction relays UP and DN. One main short circuiting lead 10 extends from contacts ca_2 to the lead 11 on the negative side of the down direction relay DN which is connected through lead 12 and contacts up_1 , with the positive potential, while the contact cg_3 at the other end of the series of contacts is connected through a main short circuiting lead 13 with the lead 14 on the negative side of the up direction relay UP, which, as will be seen is connected through lead 15 and contacts dn_1 with the positive potential.

In order to facilitate changing the point of application of the positive potential for the respective short circuits of the direction relays UP and DN, the contacts ca_2 and ca_3 to cg_2 and cg_3 are interconnected by leads 16a to 16g and 17b to 17g with the respective positive potential leads 18a to 18g, the opposite ends of the latter being arranged, by means of individual contacts, to be

further connected by contacts fa_2 and fb_3 to ff_3 and interconnecting leads $19a$ to $19e$ with the positive potential at 20 .

It will be seen that the lower series of contacts cas to cgs , operated by the call storage relays CA to CG, are arranged to cooperate with upper contact for the short circuit and lower contacts connected by leads $21a$ to $21g$ with a common lead 22 for carrying positive potential to the retardation relay SD, which is arranged to operate contacts sd_1 , sd_2 , sd_3 and sd_4 , the contacts sd_1 providing a holding circuit for the retardation relay SD from the timing device circuit TD.

It will be seen that the up direction relay UP operates contacts up_1 , up_2 , up_3 and up_4 . Of these contacts up_2 connects leads 23 from positive potential through contacts fl_1 to lead 24 connected to the up drive contactor UD and then through the common lead 25 to the brake relay E and to the negative potential. The brake relay E by operating contactor e_1 controls the application of positive potential to the brake magnet BM, either directly through lead 26 , or through lead 27 and floor relay contacts nr_1 and lead 28 . The contacts nr_1 are normally held open by operation of the floor relay NR when the lift car is at any floor, by means of an inductor plate FP, one of which is located in the lift shaft at each floor.

Down direction relay DN, the same as up relay UP, operates four contacts dn_1 , dn_2 , dn_3 and dn_4 , the contact dn_2 closing on the same lead 23 from the contact fl_1 but now to direct positive potential to the down drive contactor DD, then through the common lead 25 to complete the circuit through relay E.

A plurality of counting relays FA to FF inclusive, are provided each counting relay being provided with two magnet coils operating on a two position armature, each armature being adapted to operate a plurality of contacts, the contacts fa_2 and fb_3 to ff_3 being operated in sequence for changing the short circuit connections between the leads $18a$ to $18g$ according to the position of the lift in the shaft. The counting relays FA to FF also operate certain contacts fa_1 to fe_1 and fb_2 to ff_2 for interconnecting operating circuits for progressive and successive operation of the respective counting relays according to whether the lift is traveling up or down the shaft.

For controlling the counting relays FA to FF during up travel of the lift, alternate upper coils of the relays are connected by leads $30a$, $30c$ and $30e$ through connecting leads $31b$, $32c$, $31d$, $32e$ and contacts fb_1 and fd_1 with the upper coils of alternate counting relays, and to an impulse circuit lead 33 . The other alternate upper coils of the counting relays, that is, FB, FD and FF being connected by leads $30b$, $30d$ and $30f$ and by contacts fa_1 , fc_1 and fe_1 and leads $31a$, $32b$, $31c$, $32d$, $31e$, $32f$ with an impulse circuit lead 34 .

Similarly the lower coils of the counting relays FA to FF are connected alternately, the counting relay coils FA, FC, and FE being connected through leads $35a$, $35c$ and $35e$ with leads $36b$, $37c$, $36d$, $37e$ and $36f$, by the respective contacts fb_2 , fe_2 and ff_2 with impulse circuit lead 38 . The other alternate coils of relays FB, FD and FF being similarly connected by leads $35b$, $35d$ and $35f$ with leads $36c$, $37d$, $34e$, $37f$ with an impulse lead 39 , by contacts fc_1 and fe_1 .

The impulse circuit leads 33 and 34 are provided with oppositely placed contacts cooperating with the contactor b_2 ; and impulse circuit leads 38 and 39 are provided with oppositely placed

contacts cooperating with the contactor b_3 . The contactor b_2 is connected by lead 40 with the contact up_4 previously mentioned as operated by the up direction relay UP, and the contactor b_3 is connected by lead 41 with contactor dn_4 similarly operated by the down direction relay DN. Both of the contacts up_4 and dn_4 are arranged to be connected (it being understood that only one contact up_4 or dn_4 is closed at a time) to the lead 42 which connects with the contacts ns_1 adapted to be closed by impulse relay NS. Impulse relay NS is adapted to be operated by inductor plates IP located between floors for sending an impulse current to the counting relays for operation thereof to count the floors, that is, by operating the respective contactors fa_2 and fb_3 to ff_3 in sequence according to the direction of travel of the lift, the counting relay coils operated being determined by the contacts up_4 and dn_4 one or the other operated by the respective direction relays UP, DN to thereby determine the direction and order of sequence of the counting relays FA to FF.

The impulse current lead 42 by means of a branch 43 and contacts b_1 (in the lower position) connects with a lead 44 for actuating a holding relay A which by operating its contact a_1 provides a holding circuit through lead 45 with one coil of a two coil counting control relay B, the circuit therethrough being completed through a lead 46 to the impulse relay contacts ns_1 when the latter are released by impulse relay NS.

Operation of the counting control relay B brings into operation the second coil of this relay through the lead 47 to hold the relay operating when the holding relay A is released. As explained later, this provides for the impulse operation in succession of the counting relays FA to FF by the successive switching of the impulse current when the contacts b_2 and b_3 are shifted from one contact position to the other on the respective leads 33 , 34 and 38 , 39 .

There is a possibility that the counting relays FA to FF may lose step with the lift in the shaft or get out of synchronism therewith and for the purpose of restoring proper timing relation, a contactor TL is arranged at the top of the shaft to be operated by the lift when it reaches the end of its upward travel, this contactor by closing its contacts supplies positive potential through leads $33T$ and $34T$, which, it will be seen, are connected at the contacts b_2 with the leads 33 and 34 , to the respective counting relays so that those out of step will be operated through their upper coils to restore them to synchronism.

Similarly, at the bottom of the shaft the contactor BL when operated by the lift reaching the end of its travel downward closes its contacts and supplies positive potential through leads $36B$ and $39B$, which it will be seen are connected at contacts b_3 with the leads 38 and 39 , to the counting relays FA to FF so that any of them out of step will be operated through their lower coils to restore the relays to synchronism. The counting relays shown in the group FA—FF preferably comprise impulse operated relays of the type shown, for example in British specification No. 354,847.

Assuming that a call for floor 3 is to be made, a call button PC is depressed momentarily. As shown in the drawing, this button forms one of a number of such buttons PA—PG (one for each floor) appearing in the lift carriage, and as explained, floor buttons in the same respective circuits, one at each floor also act to call the lift.

to the floor at which a button has been depressed. As a result of the depression of the lift floor button PC call storage relay CC is operated from positive 5P on contact up_3 via contact dn_3 lead 5. 4P, push button PC contacts, lead 6C, call relay CC to negative, and the call relay locks at contact cc_1 through leads 1C and 8 to the positive 9 contact sd_2 , so that the button may be released. Contacts cc_2 and cc_3 operated by call storage relay CC remove the short-circuit from positive 20 through leads 19e to 19a, contacts ff_3 to fa_3 , lead 18a contacts ca_2 , ca_3 to cg_2 , cg_3 and lead 13 across direction relay UP, causing it to operate positive from contact dn_1 through leads 15 and 14. 15 Contact cc_3 by closing on its lower contact through lead 21C and 22 also prepares a circuit to operate retardation relay SD from positive 20 at ff_3 as explained later.

Upon operation of direction relay UP the following contacts become effective. Contact up_1 opens the positive to lead 12 and prevents false operation of direction relay DN. Contact up_2 closes a circuit from positive at fl_1 , through leads 23 and 24 which operates the "up drive" contactor unit UD and through lead 25 the brake relay E in series therewith, (see later). Contact up_3 opens at the positive 5P through lead 4P to the push button circuit and prevents further depression of push buttons from storing calls by removing positive potential from the buttons PA—PG and the like. Contact up_4 by closing on lead 40 prepares the stepping circuit through lead 42 from contact ns_1 for the counting relay chain FA—FF.

35 Brake relay E having operated upon closing of contact up_2 , contact e_1 opens the positive to lead 27 and directs it into lead 26 which energizes the brake magnet BM, removing the brake band BB from the lift motor M, and the latter commences to drive the lift L upwards under the influence of up contactor UD. When the lift has moved away from the floor at which it was standing, floor inductor relay NR is released. This relay NR is of known type, comprising a permanent or electro-magnet and an armature, fixed to the lift, the armature being moved as the relay passes an inductor plate FP in the lift shaft. As previously pointed out, when the lift passes some point intermediate between floors, contacts ns_1 are operated momentarily by the impulse inductor relay NS, which is also of the inductor type, but acted upon by inductor plates IP, different from those operating the floor inductor relay NR. When contact ns_1 closes, the positive on lead 46 is opened and positive directed through lead 42 to an intermediate relay A which operates via lead 43 and contact b_1 . Contact a_1 is thereby operated and prepares to lock the intermediate holding relay A in series with counting control relay B. The positive from contact ns_1 also applies potential to the counting chain relay FA via lead 42 contact up_4 , lead 40 and contact b_2 , leads 33 and 30a thus operating the first counting relay FA to an opposite position from that shown, and by so doing moving the contacts fa_1 and fa_2 . The contact fa_1 by closing prepares a circuit to operate counting relay FB at the next impulse. Contact fa_2 by moving from lead 18a to 18b transfers the path of the positive from ff_3 , previously short-circuiting direction relay UP from contact ca_3 to contact cb_3 .

When impulse inductor relay NS releases after passing the first inductor plate IP, contact ns_1 by closing on lead 46 operates counting control relay B in series with holding relay A via con-

tact a_1 , thus holding relay A when contact b_1 opens. Contact b_1 moved onto the upper contact on lead 47 prepares to hold counting control relay B when lead 42 is energized at the next operation of impulse inductor relay NS which will then open the circuit through the upper coil of control relay B and likewise open the holding circuit through lead 45 and contact a_1 of holding relay A. Operation of control relay B moves contact b_2 onto its lower contact, on lead 34 which prepares to operate the second counting relay FB.

The lift now passes floor 2 (the second floor inductor plate FP operates floor inductor relay NR but contacts up_3 being open nothing happens), and later, passing the impulse inductor plate IP between floors 2 and 3 momentarily operates impulse inductor relay NS once more. This again operates contact ns_1 which by opening the lower contact on lead 46 releases holding relay A and counting control relay B via its second coil. This impulse also operates counting relay FB over the previously described path through up_4 but now from lead 40 through b_2 on the lower contact, lead 34 and contact fa_1 , 25 leads 32b and 30b.

Operation of counting relay FB moves contact fb_1 to close on leads 31b and 33 to switch the impulsive circuit to the upper contact of b_2 and connect with counting relay FC through leads 32c and 30c. At the same time contact fb_3 moves onto the upper contact transfers the previously described short-circuiting path from lead 19a to lead 18c and to contact cc_3 , which is in an operated position (call storage relay CC operated); thus positive from 20 and contact ff_3 through leads 21c and 22 operates retardation relay SD. Upon operation of retardation relay SD contact sd_1 closes and locks this relay SD to the time delay device through lead TD. Contact sd_2 opens 40 and cuts the positive at 9 from lead 8, thus de-energizing call storage relay CC, which releases. Contact sd_4 closes and through lead 50 energizes the "slow-down" contactor DS.

Releasing call storage relay CC releases contacts cc_2 and cc_3 which restores the short circuit from positive 20 and contacts ff_3 on direction relay UP, the latter releases and cuts the circuit of the up drive contactor UD and brake relay E at contact up_2 . Contact cc_3 moving off lead 21c 50 opens the circuit to retardation relay SD but this is held from the timing device. Brake relay E released, contact e_1 opens and cuts the positive through lead 26 but through the lower contact the positive goes to lead 27 and through contact nr_1 and lead 28 holds brake magnet BM but prepares to release the brake magnet when floor impulse relay NR is operated and opens contact nr_1 .

Through operation of the slow-down contact DS, the lift now commences to slow down, approaching floor 3. When it arrives at the floor, floor inductor relay NR is energized by a floor inductor plate FP and the contact nr_1 opens, de-energizing the brake magnet BM, which releases the brake BB and stops the lift at the required 65 floor.

Retardation relay SD, which is being held by the time delay TD, is shortly released by the time delay circuit, allowing sufficient time, by holding open contact sd_3 so that new calls cannot be registered for the lift, for the floor gate at the third floor to be opened. This action, that is, opening the third floor gate, releases gate relay FL, since switch CC, one of the floor gate switches GA—GG is opened. It will be understood that 75

the gate relay FL, may be released by an emergency switch GL located in the lift carriage as the "emergency stop" button. Release of gate relay FL, with the opening of contact f_1 prevents energization of either the "up" or "down" drive contactors UD or DD until all conditions are favorable, as contact f_1 removes their energizing positive potential from lead 23 and contacts up_2 and dn_2 .

10 If a passenger now enters the lift at the third floor and depresses a button necessitating travel in a downward direction, operations occur similar to those already described except that the previously mentioned short-circuit formed by 15 the contacts of call storage relays CA—CG is broken in a different place; that is, so as to open the short circuit on the down direction relay and direction relay DN is this time energized, and due to the operation of the down drive contactor 20 DD by the closing of contact dn_2 , the lift travels downward. Since contact dn_4 is now closed instead of contact up_4 the counting relay chain FA to FF is this time impelled in a manner similar to that already described, but in a reverse direction, the impulses being supplied from contact ns_1 via contact dn_4 , lead 41 and contact b_3 to the lower coils of the counting relay group FA—FF. This will restore in succession armatures and contacts previously operated by the up- 25 per coils.

As there is always a possibility that an impulse may be missed and the counting relay chain FA—FF get out of step, means are provided for ensuring restoration of synchronism each time the lift reaches its upper or lower limit of travel. These means are shown as mechanically operated contactors, TL at the top and BL at the bottom of the shaft, the contactor TL being operated by the lift when the lift is at the top floor, and contactor BL when the lift is at the bottom floor. If, for example, the lift should reach the top floor with only counting relays FA, FB and FC operated, the contactor TL will close its contacts. The closure of its contacts by contactor TL directs positive potential through leads 33T, 33 and 34T, 34 supplying positive potential first to relay FD via leads 34, 30a, contact fa_1 leads 32b and 31c, contact fc_1 and leads 32d and 30d. Contact fd_1 is then closed and the positive from TL through lead 33 similarly operates counting relay FE, which by closing contact fe_1 operates counting relay FF, thus restoring the counting relays to synchronism. A similar action, only operating the counting relay chain in the reverse direction, through leads 38B, 38 and 39B, 39, occurs when the lift reaches the bottom floor, and contactor BL is operated. Other contacts operated by contactors TL or BL could be arranged to open the lift driving circuit in known manner if required. 60 Several modifications may be made to the system outlined above, without departing from the scope of the invention. For example, each of the relays FA—FF may be of the latching type, i. e. having an armature which when operated by one coil is held in position by a latch, the latch being removed and the armature restored to normal by the energization of a second coil. This type of relay is shown in British specification No. 208,075. Again the relays A and B may be replaced by a simple impulse-operated device similar to a step-by-step switch, and adapted to change over a contact for every impulse. Further, the acceleration and deceleration of the lift may be under control of apparatus of the type disclosed 65 in U. S. application No. 738,963. In addition fur-

ther contacts of the relays FA—FF may be caused to light indicating lamps in the lift carriage or at the various floors, showing the position of the lift at any instant. Other modifications will be obvious to those skilled in the art, and the invention is to be understood to cover such modifications, subject to the scope of the appended claims. 5

We claim:

1. In a lift system serving a plurality of floors, up and down direction relays, a plurality of floor push button circuit connections arranged to operate said relays for rearranging the system for the respective up and down movements of the lift, control circuits interconnected by a plurality of contactors, a chain of two-position counting 15 relays for operating the contactors in said circuits so as to arrange the circuits for controlling operation of the respective up and down relays according to the position of the lift and the direction of travel to the floor required and current 20 impulse means arranged to be operated by the lift in passing from floor to floor for operating the counting relays in succession to thereby change the arrangement of said circuit connections according to the floors passed. 25

2. In a lift system serving a plurality of floors, up and down direction relays, a plurality of floor push button circuit connections for operating said direction relays, interconnected circuits for controlling up and down travel of the lift, a chain 30 of two position counting relays for the respective floors to be served, contactors in said interconnected circuits controlling the up and down direction relays, a plurality of two-position counting 35 relays arranged to operate said contactors for changing the circuit connections according to the position of the lift and current impulse means for operating said counting relays in succession as the lift moves from floor to floor, said counting relays being actuated to assume one position and 40 effect circuit connections in one direction of sequence when the lift is going up and to assume the other position and effect circuit connections in the opposite direction when the lift is going down. 45

3. In a lift system serving a plurality of floors, a direction relay for up movement and direction relay for down movement of the lift, floor push button circuits and connections for controlling operation of the respective direction relays, interconnected circuits for normally short circuiting said direction relays, a plurality of call storage contactors in said direction relay short circuiting connections for changing the connections for one and opening the short circuit for and operating the other direction relay, call storage relays for respective floors operated by the respective floor push button circuits for operating said call storage contactors, a plurality of counting contactors in said direction relay short circuiting 50 connections for varying the point of application of the short circuiting potential according to the position of the lift, the arrangement being such that one or the other of said direction relays is operated upon operation of a floor push button according to the point of application of the short circuiting potential as determined by the position of the lift and the direction of travel required, a plurality of two-position counting relays for 55 operating said counting contactors and circuits and current impulse means arranged to be operated by the lift in its movement from floor to floor for actuating said two-position counting relays in succession to position the same according 60

55

65

70

75

to the position of the lift and its direction of travel.

4. In a lift system serving a plurality of floors as in claim 3, a retardation relay having circuit connections arranged to be completed by contactors operated by said call storage relays and by said two-position counting relays, the arrangement being such that the retardation relay is operated automatically when the corresponding counting relay is operated, operation of said retardation relay being arranged to release the operated call storage relay.

5. In a lift system serving a plurality of floors, an up direction relay and a down direction relay for controlling corresponding movements of the lift, a plurality of contactors and circuit connections normally applying potential to short circuit both of said direction relays, the arrangement being such that one or the other of said 20 direction relays is operated by removing the corresponding short circuit according to the contactor operated as determined by the position of the lift and the direction the lift is required to travel, a plurality of two-position counting relays arranged in a chain for operating certain of said contactors for changing the point of application of the short-circuiting potential in said circuit

connections according to the position of the lift, means operated by the lift in passing from floor to floor for supplying current impulses for operating the two-position counting relays in sequence, relays and circuits for determining the direction of sequence operation of said counting relays according to the direction of travel of the lift, floor call storage relays for operating certain of said contactors for removing the corresponding short circuit for the operation of one or the other of said direction relays according to the position of the lift and the direction of travel required and means for reestablishing the short circuit and releasing the corresponding direction relay when the lift reaches the floor of the call 15 storage relay operated.

6. In a lift system serving a plurality of floors as in claim 5, circuit connections cooperating with contactors arranged to be operated by the lift in predetermined extreme positions of travel 20 for supplying potential for automatically operating in succession any of said two-position counting relays that may have become out of step with the lift in its travel to one extreme position or the other to thereby restore synchronism. 25
